KNITTED FABRIC.

No. 17,873.

Patented Nov. 8, 1887.

UNITED STATES PATENT OFFICE.

OLIVER T. JENNINGS, OF BROOKLYN, NEW YORK, ASSIGNOR TO A. G. JENNINGS & SONS, OF SAME PLACE.

DESIGN FOR A KNITTED FABRIC.

SPECIFICATION forming part of Design No. 17,873, dated November 8, 1887.

Application filed March 11, 1887. Serial No. 230,562. Term of patent 7 years.

To all whom it may concern:

Be it known that I, OLIVER T. JENNINGS, a citizen of the United States, and residing at Brooklyn, Kings county, New York, have invented and produced a new and original Design for Knitted Fabrics, of which the following is a specification, reference being had to the accompanying photograph, forming part of this specification, which is a face view of a piece of knitted fabric embodying my new design.

My design consists of the knitted fabric A, having alternate rectangular fields *a* and *b*. The rectangular fields *a* are close-meshed, the rows of meshes being of chain-like appearance, and the rectangular fields *b* are open-

meshed, having therein peculiar irregular zigzag lines, forming irregular rhomboids, as shown.

I claim—

The design for a knitted fabric herein shown and described, the same consisting of the close and open meshed alternating rectangles *a* and *b*, the rectangles *a* having rows of meshes of chain-like appearance, and the rectangles *b* having peculiar irregular zigzag lines forming irregular rhomboids, as shown. 20 25
